Filed Feb. 26, 1968, Ser. No. 10,706

Term of patent 14 years

Int. Cl. D8—03; D6—01

U.S. Cl. D33—3

FIGURE 1 is a front elevational view of a fishing rod rack or the like showing my design;

FIG. 2 is a perspective view from one side and below of the left support member of FIG. 1;

FIG. 3 is a side plan view of the other side of the left support member of FIG. 1;

FIG. 4 is a perspective view from one side and below of the right support member of FIG. 1; and

FIG. 5 is a side plan view of the other side of the right support member of FIG. 1.

The dotted line showing of fishing rod fragments in FIGURE 1 is for illustrative purposes only.

The dominant features of my design reside in those portions shown in full lines on the drawing.

I claim:

The ornamental design for a fishing rod rack or the like, substantially as shown and described.
